UNITED STATES PATENT OFFICE

HUBERT E. GORSUCH, OF SPRINGFIELD, OHIO

DESIGN FOR A COMBINED THERMOMETER AND PAPER CLAMP

Application filed April 27, 1931. Serial No. 39,638. Term of patent 3½ years.

To all whom it may concern:

Be it known that I, HUBERT E. GORSUCH, a citizen of the United States, residing at Springfield, in the county of Clark and State of Ohio, have invented a new, original, and ornamental Design for Combined Thermometer and Paper Clamp, of which the following is a specification, reference being had to the accompanying drawings, forming part thereof.

Fig. 1 is a front elevation and Fig. 2 is a side elevation of a combined thermometer and paper clamp showing my new design.

I claim:

The ornamental design for a combined thermometer and paper clamp as shown.

HUBERT E. GORSUCH.
